UNITED STATES PATENT OFFICE.

MARTIN L. CONNETT, OF BELLEFONTAINE, OHIO, ASSIGNOR, BY MESNE ASSIGNMENTS, TO MATTHEW F. CONNETT AND JOHN HALE MORSE, BOTH OF KANSAS CITY, MISSOURI.

FABRIC-TURFING IMPLEMENT.

SPECIFICATION forming part of Letters Patent No. 409,139, dated August 13, 1889.

Application filed August 16, 1888. Serial No. 282,843. (No model.)

To all whom it may concern:

Be it known that I, MARTIN L. CONNETT, a citizen of the United States, residing at Bellefontaine, in the county of Logan and State of Ohio, have invented a new and useful Improvement in Fabric-Turfing Implements, of which the following is a specification.

My invention relates to improvements in fabric-turfing implements in which a reciprocating threaded needle is operated to puncture the fabric in its downward or forward movement, carrying with it the thread, and in its backward or upward movement withdrawing only a part of the thread to produce a loop of the latter on the rear or under side of the fabric; and the objects of my improvements are, first, to provide an automatically-operative lock to stop the feed of the thread in the upstroke of the needle, and thereby 15 avoid the use and disadvantages of the tension mechanism, impingers, or plungers commonly employed in such devices to control the feed of the thread; second, to produce a turfing implement in which the needle employed may be an ordinary sewing-machine needle of any desired degree of fineness; third, to produce a turfing implement of comparatively few parts which shall be compact in form, durable and reliable, and convenient 20 in its operation.

My invention consists in the general construction of my improved device; and it further consists in details of construction and combinations of parts.

In the drawings, Figures 1, 2, 3, and 4 are 35 views in side elevation of my improved device, illustrating the relative positions of parts during different stages of the operation; Fig. 5, a similar view, partly sectional, showing 40 the internal construction; Fig. 6, a perspective view of a detail; Fig. 7, a similar view of the whole device, except the details shown in Figs. 6 and 8, with parts detached; and Fig. 8, a similar view of a detail.

C is a holder in the form of a sheath, and E a presser-foot formed, preferably, from a single length of stiff wire, and fastened at its opposite ends upon the back of the sheath.

B is a needle-bar open on one side and

longer than the sheath C, in which it is adapted 50 to be reciprocated. Toward one end the needle-bar is provided in its lateral edges with corresponding notches *t* adjacent to its open or forward side, and toward the opposite end it is cut away on its rear side to afford a recess 55 for a block G. Adjacent to the recess the extremity of the rear side of the needle-bar is flanged outward to produce the stop I, which limits the upward movement of the needle-bar by striking against the end *y'* of 60 the sheath, as hereinafter described.

The block G is pivotally secured in the needle-bar by a pin *s*, which passes through a perforation *s'* in the block and rests at opposite ends in bearings *s''* in the needle-bar. 65 The rear side of the block G is cut away and beveled, as shown, toward its upper extremity, which extends above the recess and stop I, so that as the block rests against the rear side of the needle-bar, which it does normally, 70 as hereinafter described, its position is slightly oblique with reference to the needle-bar.

On its forward side the block G is provided with a narrow extension or lug *G'*, which is recessed on its under side to afford an oblique 75 slot *p*. A needle-socket *q* extends from the bottom of the block toward the upper extremity of the latter, and a clamp-screw *H*, for clamping the needle, enters the socket from the rear of the block G. An eye *o* extends 80 from a point adjacent to the socket *q* at the bottom of the block diagonally through the latter and lug *G'*, crossing the slot *p* near the inner extremity of the latter.

K is a stirrup, comprising a strip of spring- 85 wire doubled to render two parallel lengths, which are curved, as shown at *x x*, and secured at their free ends in a knob or handle A. The stirrup K is within the needle-bar, with its knob at the top of the latter and its 90 loop end *K'* engaging the oblique slot *p* in the lug *G'*.

The reciprocation of the needle-bar in its sheath is produced by pressure upon the knob to cause it to bear against the upper extremity of the needle-bar and force the latter down, and raising the knob to cause the loop end *K'* of the stirrup to engage the inner end of the

slot *p* and draw the needle-bar up. The length of the stirrup is slightly in excess of the distance from the upper extremity of the needle-bar to the inner end of the slot *p*, whereby 5 the end *K'* has limited play in the slot across the path of the eye *o* and operates as a lock to control the feed of a thread, as hereinafter described.

The curves *x* in the stirrup permit the latter to rest against opposite sides of its casing, which causes the stirrup toward its loop end to operate as a spring and bear against the face of the block *G* to retain the latter normally against the rear side of the needle-bar, 15 as before described.

D is a flat curved friction-spring, which extends longitudinally of the needle-bar between the open side of the latter and the sheath. The spring *D* is bent and doubled 20 over toward one end to produce a head comprising lateral projections on opposite sides, which afford, respectively, a catch *t'*, to engage the notches *t*, before referred to, in the needle-bar, and a stop *D'*. Of course the head 25 may be formed in any other convenient way. The engagement of the catch *t'* with a pair of notches *t* causes the spring *D* to travel with the needle-bar as it reciprocates and produce increased frictional contact between the latter and the sheath to overcome the tendency 30 of the needle-bar to descend by its own weight without pressure upon the knob, and to permit initial lowering of the stirrup to unlock the thread, as hereinafter described. In the 35 downward plunge of the needle-bar the stop *D'* strikes against the upper edge *y* of the sheath, and it may be adjusted to shorten or lengthen the plunge by engaging the catch *t'* with notches *t* of different heights.

40 The operation is as follows: A needle *F*, having an eye toward its point, is adjusted in the needle-socket *q* and secured by means of the clamp-screw *H*. When thus adjusted, the needle extends normally obliquely forward, owing to the angle at which the block *G* is held by the spring-stirrup, as before described. A slight backward pressure against the needle will cause it and the pivotal block *G* to turn to a position in line with the needle-bar, as shown by dotted lines in Fig. 4, from which when released it will spring to its normally-oblique position. A thread *J* of the material desired to produce the turf is passed through the eye *o* from the upper side 50 of the lug *G'*, crossing the slot *p* between the inner extremity of the latter and the end *K'* of the stirrup. The end of the thread is then passed through the eye of the needle. The oblique position of the needle causes it in its 55 downward plunge to enter the fabric at an angle, and as it descends draw the device forward a certain distance governed by the angle of its inclination and the extent of the plunge below the presser-foot. The needle is 60 prevented from yielding in a forward direction by the impingement of the upper part of the block against the rear of the needle- 65

bar, as before described. As the needle is raised, however, the pressure of its forward side against the fabric causes the needle to 70 vibrate backward and ascend in a direct line with the needle-bar and spring to its oblique position again when released. Thus each descent of the needle through the fabric causes the presser-foot to travel forward automatically a predetermined distance without corresponding backward movement during the ascent of the needle. The play of the end *K'* of the stirrup in the slot *p* causes the former before the ascent of the needle-bar to 80 clamp the thread *J* against the inner extremity of the slot *p* and to release the thread before the descent of the needle-bar. Thus in the operation of the device as the needle descends through the fabric the thread pays 85 out through the eye *o* until the needle reaches its lowest position, while during the ascent of the needle-bar the thread is locked, preventing further feed of the material and causing the ascending needle to withdraw part of the 90 thread that has been carried through the fabric, and thereby produce a loop of desired size on the under side of the latter.

By adjusting the stop *D'* to different heights on the needle-bar, as before explained, 95 the lengths of loops and stitches may be gaged, as desired, according to the fineness of the needle and thread employed.

What I claim as new, and desire to secure by Letters Patent, is—

1. In a fabric-turfing implement in which a needle-bar is operated to reciprocate a threaded needle through a fabric, the combination, with the needle-bar, of a clamp for the thread between the thread-supply and the eye of the needle, connected with and movable with the needle-bar, and operating by the reciprocation thereof alternately to lock and unlock the thread in the progress of the latter to the eye of the needle, substantially as described. 100

2. In a fabric-turfing implement in which a needle-bar is operated to reciprocate a threaded needle through a fabric, a clamp for the thread upon and movable with the needle-bar, and a handle upon the needle-bar connected with the clamp and having limited play independent of the needle-bar to open and close the clamp, whereby movement of the handle to advance the needle-bar first opens the clamp and unlocks the thread, and movement of the handle to withdraw the needle-bar first closes the clamp and locks the thread, substantially as described. 115

3. In a fabric-turfing implement, the combination, with the holder, of a reciprocating needle-bar carrying toward one end a block *G*, provided with a needle-socket *q*, a slot *p*, and an eye *o*, and a stirrup *K*, movable in the slot *p* and connected with a handle *A*, substantially as described. 125

4. In a fabric-turfing implement, the combination, with the holder, of a reciprocating needle-bar carrying toward one end a pivotal block *G*, provided with a needle-socket

- q, a slot p, and an eye o, and a spring-stirrup K, movable in the slot p and bearing against the pivotal block G, substantially as described.
5. In a fabric-turfing implement, the combination, with the holder C and presser-foot E, of a reciprocating needle-bar within the holder carrying toward one end a pivotal block G, provided with a needle-socket q, a slot p, and an eye o, and a spring-stirrup K within the holder, having a handle at one end and bearing toward its opposite end against the pivotal block G, with its extremity in the slot p, in which it has limited play to clamp and release alternately a thread in the eye o, substantially as described.
- 10 6. In a fabric-turfing implement, the combination, with the holder C and presser-foot E, of a channeled reciprocating needle-bar B within the holder, carrying toward one end a pivotal block G, provided with a needle-socket q, a slot p, and an eye o, and a spring-stirrup K within the channel of the needle-bar and provided at one end with a handle A, and extending at the other end into the slot p and bearing against the block G, and of such length as to have limited play within the slot, whereby it clamps the thread when the needle is withdrawn and releases it as the needle is advanced, substantially as described.
- 15 7. In a fabric-turfing implement, the combination, with the holder C, reciprocating needle-bar B, provided toward its upper extremity with notches t and carrying at its opposite end a needle, and locking mechanism to clamp the thread when the needle is withdrawn and release it when the needle is advanced, of a friction-spring D, interposed between the holder and needle-bar and provided with a head affording a stop D' and catch t' to enter the notches t, substantially as described.
- 20 8. In a fabric-turfing implement, the combination, with the holder C and presser-foot E, of a channeled reciprocating needle-bar B within the holder, provided with a recess at one end and a stop I adjacent to the recess, a block G, pivoted to the needle-bar, provided with a needle-socket q, a slot p, and an eye o, and a spring-stirrup K within the channel of the needle-bar and provided at one end with a handle A, and extending at the other end into the slot p and bearing against the block G, and of such length as to have limited play within the slot, whereby it clamps the thread when the needle is withdrawn and releases it as the needle is advanced, substantially as described.
- 25 9. In a fabric-turfing implement, the combination, with the holder C, presser-foot E, and channeled reciprocating needle-bar B, carrying toward one end a pivotal block G, provided with a needle-socket q, a slot p, and an eye o, of a curved spring-stirrup K, extending through the channel of a needle-bar and bearing against opposite sides of its casing to provide a spring toward one end which bears against the block G, and extending at its extremity into the slot p, and provided at its opposite end with a handle A, the stirrup being of such length as to have limited play within the slot, whereby it clamps the thread when the needle is withdrawn and releases it as the needle is advanced, substantially as described.
- 30 10. A fabric-turfing implement comprising, in combination, a holder C, carrying a presser-foot E, a channeled reciprocating needle-bar B within the holder, having a stop I toward one end and notches t toward its opposite end, and carrying a pivotal block G, provided with a needle-socket q, a slot p, and an eye o, a spring-stirrup K within the channel of the needle-bar and bearing against opposite sides of its casing, provided at one end with a handle A, and extending at the other end into the slot p and bearing against the block G, the stirrup being of such length as to have limited play within the slot, whereby it clamps the thread when the needle is withdrawn and releases it as the needle is advanced, substantially as described.
